UNITED STATES PATENT OFFICE.

LOUIS NOVOTNY, OF VALPARAISO, NEBRASKA.

BUSHING-REMOVING TOOL.

Application filed June 14, 1923. Serial No. 645,337.

To all whom it may concern:

Be it known that I, LOUIS NOVOTNY, a citizen of the United States of America, residing at Valparaiso, in the county of 5 Saunders and State of Nebraska, have invented certain new and useful Improvements in Bushing-Removing Tools, of which the following is a specification.

This invention relates to certain new and 10 useful improvements in bushing removing tools and has particular reference to a tool for removing the bushing of a piston.

The primary object of the invention is 15 to provide a tool for removing bushings from pistons wherein a tool rod has a head detachably mounted upon one end thereof for entering the transverse bore of a piston and further having a block slidably mounted upon the tool rod for possessive engagement with an abutment carried by the rod in forcing a bushing from a piston.

With the above and other objects in view 20 as the nature of the invention is better understood, the same consists of the novel 25 form, combination and arrangement of parts hereinafter more fully described shown in the accompanying drawing and claimed.

In the drawing, wherein like reference 30 characters designate corresponding parts throughout the several views,

Figure 1 is a side elevational view of a 35 bushing removing tool with a portion of a piston partially illustrated in section associated with the tool with the hammer block and removable head for the tool shown in section, the hammer block being further illustrated in a dotted line position showing the operation thereof, and

Figure 2 is a top plan view of the tool.

Referring more in detail to the accompanying drawing, the bushing removing tool is illustrated as operatively associated with a piston 1 having the usual transverse bore 2 in which a bushing 3 is removably positioned.

The tool for removing the bushing 3 from the piston 4 embodies an elongated shank 4 having an integral head 5 formed at the outer end thereof while the inner end 45 of the rod 4 is threaded as at 6.

A solid cylindrical head 7 carrying an annular outwardly directed flange 8 carries a polygonal inner extension 9, inwardly of the flange 8 that is socketed and internally threaded as illustrated in Fig. 1 to receive the threaded end 6 of the tool rod

4, the polygonal portion 9 facilitating the mounting of the head 7 upon the threaded end of the rod.

A sliding block is mounted upon the rod 60 4, and includes an elongated tubular collar portion 10 having an enlarged head 11 at one end thereof adapted for ready gripping of the block, the integral head 5 at the outer end of the rod limiting movement of 65 the block in one direction, while the pin 12 extending transversely of the rod 4 and projecting from opposite sides thereof as illustrated limits movement of the sliding block in the opposite direction.

In the use of the device, it being noted 70 that the removable head 7 is of a size that is freely received in the bore 2 of the piston, is placed in the outer end of the piston 4 and the block slideable upon the rod is 75 forcefully moved thereover to strike the transverse pin 12 to cause the head 7 to strike the adjacent end of the piston bushing 3, removing the same from the piston bore 2 as illustrated in Fig. 1, movement 80 of the rod 4 and head 7 transversely of the piston being limited by the flange 8 adapted for engagement with the outer face of the piston as will be obvious from an inspection of Fig. 1. Removable mounting of the head 85 7, permits substitution of heads of various sizes for association with piston bores of different diameters, rendering the tool substantially universal in its use by the substitution of the desired head 7. If desired, 90 the sliding block may be gripped by the operator and an implement employed for striking the rod head 5 to remove the bushing, the rod freely sliding through the block.

While there is herein shown and described 95 the preferred embodiment of the present invention it is nevertheless to be understood that minor changes may be made therein without departing from the spirit and scope 100 of the invention as claimed.

What is claimed as new is:—

1. In a bushing removing tool for pistons, a rod having an integral head at one end, a removable head having an outwardly directed annular flange carried by the other end of the rod, a transverse pin carried by the rod adjacent the removable head and a block slideable on the rod between the integral head and pin to forcefully strike the pin and move the removable head into engagement with a bushing.

2. In a tool for removing bushings from pistons, the combination with a piston having a transverse bore and bushing therein, of a tool having a removable head entering the piston bore for engagement with the bushing, an annular flange carried by the removable head adapted for engagement with the side wall of a piston to limit movement of the head into the piston bore, and a block slidably mounted on the rod.
3. In a tool for removing bushings from pistons, the combination with a piston having a transverse bore and bushing therein, of a tool having a removable head entering

the piston bore for engagement with the bushing, an annular flange carried by the removable head adapted for engagement with the side wall of a piston to limit movement of the head into the piston bore, a transverse pin carried by the rod adjacent to the removable head, a head integral with the other end of the rod and a block slidably on the rod between the integral head and pin.

In testimony whereof I affix my signature.

LOUIS NOVOTNY.
